UNITED STATES PATENT OFFICE.

HERBERT E. KIMBALL, OF DALLAS, TEXAS.

GRAVE-MARKER.

1,095,885.

Specification of Letters Patent.

Patented May 5, 1914.

Application filed July 11, 1913. Serial No. 778,608.

To all whom it may concern:

Be it known that I, HERBERT E. KIMBALL, a citizen of the United States, residing at Dallas, in the county of Dallas and State of Texas, have invented a new and useful 5 Grave-Marker, of which the following is a specification.

The present invention appertains to a grave marker or cradle, and aims to provide 10 a novel and improved device of that character.

One object of the present invention is to provide a grave marker or cradle which shall eliminate the necessity or use of the 15 ordinary mound, as well as the usual tombstone at the head of the grave.

Another object of the present invention is to provide a device of the nature indicated which may be set over the grave, to surround 20 the same, and which shall be so constructed as to prevent its sinking into the soil, tilting, or being otherwise casually displaced.

Another object of the invention is to provide 25 a device of the character specified which shall surround the grave, and which shall provide a flower bed over the grave, the device being so constructed as to destroy the grass and other vegetation thereunder, and 30 to prevent grass or other foreign vegetation from finding its way to the flower bed.

Another object of the present invention is to provide a grave marker or cradle provided with novel means for holding bouquets. 35

With the foregoing and other objects in view which will be apparent as the description proceeds, the invention resides in the combination and arrangement of parts and 40 in the details of construction hereinafter described and claimed, it being understood that changes in the precise embodiment of the invention herein disclosed can be made within the scope of what is claimed without departing from the spirit of the invention. 45

The invention has been illustrated in its preferred embodiment in the accompanying drawing wherein—

Figure 1 is plan view of the improved 50 grave marker or cradle, the cover or lid of the photograph holder being swung open. Fig. 2 is a longitudinal section taken on the line 2—2 of Fig. 1, the cover or lid of the photograph holder being closed. Fig. 3 is 55 an enlarged sectional detail taken on the line 3—3 of Fig. 1.

The body of the improved grave marker or cradle is elongated or somewhat elliptical in contour, and its central portion is open, in order that the grave marker or cradle 60 may surround a grave, it being understood at the outset, that the present device may be constructed in various sizes to accommodate various sizes of graves.

The body of the marker or cradle embodies an endless inverted channel 1, which is preferably cast from suitable metal having sufficient inherent tenacity or rigidity to withstand the conditions to which the device is subjected. The inverted channel 1 has its 70 back formed with a ridge 2, the outer and inner sides of the ridge being preferably of ogee section, or being of other suitable configuration for purpose of beauty in design or appearance. The channel 1 is filled with 75 concrete 3, or any other plastic filling, which is worked flush with the edges of the flanges of the channel, so as to provide a flat base of relatively large area or width.

At one end, the back of the channel 1 is 80 formed with a rounded portion 4 over its ridge, the portion 4 being preferably integral with the channel, and being adapted to receive a suitable inscription plate 5. The inscription plate 5 may be fashioned from 85 aluminium or other wear-resisting material, which may be inscribed in any suitable manner, the inscription plate 5 being preferably in the form of a scroll partly unrolled. The inscription plate 5 is preferably provided at 90 the foot of the grave marker or cradle, while at the other end, the channel is provided with the photograph holder including the hinged cover 12.

The sides of the marker or cradle are 95 equipped with suitable bouquet holders 16, which may be in the form of vases or the like. As illustrated, four of the bouquet holders or vases 16 are employed, two for each side. The bouquet holders or vases 16 are applied 100 to the channel 1 in a peculiar manner. Thus, each of the holders or vases 16 is provided with a lower saddle 17 straddling or sitting astride the ridge 2 of the channel over an aperture provided in the ridge, to prevent the holder 16 from turning or rotating. A bolt 18 is passed upwardly through the ridge of the channel and is inserted into the shank or lower portion of the holder or vase 16, to clamp the saddle 17 over the ridge. It 110 is to be understood that the holders or vases 16 are applied over the ridge of the channel

prior to the introduction of the filling 3 into the channel, so that after the filling is inserted to embrace the heads of the bolts 18 fitting within the ridge, it will be impossible 5 to unscrew the bolts 18, and consequently, the bouquet holders or vases will be securely locked to the channel, in order that they may not be removed by malicious persons.

The outer or exposed sides or surfaces of 10 the channel are preferably porcelainized or otherwise finished, to imitate marble, stone, or the like, and for the purposes of wear. By finishing the exposed surface of the channel with porcelain, or its equivalent, the 15 channel will be prevented from corroding, and at the same time, the marker or cradle will have the appearance of an ordinary marble cradle, or the like, as prevailing at the present day. If desired, the photograph 20 holder 6 may also be finished similar to the channel, which is also true of the cover or lid 12 for the photograph holder, and the bouquet holders or vases. It is to be understood that the bouquet holders or vases 25 16 are preferably constructed of suitable metal or other wear-resisting material.

The present device, as a whole, will be of 30 pleasing design or appearance, which is an essential element in a device of this character. Furthermore, the present device is 35 peculiarly adapted for the purposes for which it is designed.

In use, the grave is leveled, the mound 35 therefore being eliminated, and the marker or cradle is set over the grave properly. The cradle will thus provide a flower bed within the same, the flower bed being on the same level as the surrounding soil. Before 40 setting the cradle in position, the grass or vegetation is preferably cut away surrounding the grave, and after the cradle has been positioned, it will be observed that the weight thereof will prevent any vegetation from growing underneath the same, and in

this manner, grass and other vegetation will 45 be prevented from growing underneath the cradle to the flower bed. The base of the cradle or marker is relatively wide, or has a comparatively large area, so as to sit flatly 50 on the soil surrounding the grave, to prevent the dislodgment of the cradle from its proper or set position. The present cradle may even be employed on sandy soils, without the liability of the cradle sinking into 55 the soil, or tilting, as might be the case if the supporting surface were not of considerable area. The present device may be inexpensively manufactured, and will provide an efficient and economical substitute for the ordinary marble marker or cradle. 60

From the foregoing, taken in connection with the drawings, the other advantages of the present device will be apparent to those versed in the art, it being observed that the objects aimed at have been carried out satisfactorily, and that the present device is a desirable one for the purposes for which it is intended. 65

Having thus described the invention, what is claimed as new is:

In a device of the character described, a 70 grave cradle embodying an inverted channel, the back of which is formed with a longitudinal ridge, the ridge being provided with an aperture, a vase having a lower saddle straddling the said ridge over the aperture, a bolt passed upwardly through the said aperture and threaded into the vase, the head of the bolt fitting within the said ridge, and a plastic filling for the channel 75 80 embracing the bolt head.

In testimony that I claim the foregoing as my own, I have hereto affixed my signature in the presence of two witnesses.

HERBERT E. KIMBALL.
